UNITED STATES PATENT OFFICE.

ANDREW GANTZ, OF YOUNGSTOWN, OHIO.

OPEN-HEARTH-FURNACE DOOR FRAME.

Application filed August 11, 1923. Serial No. 656,801.

To all whom it may concern:

Be it known that I, ANDREW GANTZ, a citizen of the Republic of Hungary, residing at Youngstown, in the county of Mahoning and State of Ohio, have invented new and useful Improvements in Open-Hearth-Furnace Door Frames, of which the following is a specification.

This invention relates to open hearth furnaces, particularly to the door frames thereof, and has for its object the provision of a novel frame of hollow formation through which water is circulated for the purpose of effecting cooling, the essential feature of the invention being the provision of upstanding pedestals on the frame which support the iron work of the roof, the arrangement being such that an inspection may be made at any time to ascertain the conditions so that any defects may be discovered and remedied.

Another object is the provision of a structure of this character which is so constructed as not to be injured in case the roof is punched through by the loading machine which is commonly provided for effective charging of the furnace with the necessary materials.

A most important feature is the provision of a furnace structure and door frame arrangement in which the weight of the roof never comes upon the door frames so that they will not ever bend out of shape as occurs so frequently in the ordinary type of furnace, it being well known that such bending and sagging leaves a hole which permits a draft and causes the escape of gas.

Still another important object is the provision of a furnace structure of such a character that whenever the top is raised for any reason the resultant opening between the top of a door frame and the top structure may be simply filled in with bricks.

An additional object is the provision of a frame of this character which, if preferred, may be equipped with a slidably mounted door which can be kept closed ordinarily but which is readily capable of being opened whenever such is desired for any reason.

A further object is the provision of a structure of this character which will be simple and inexpensive to manufacture, easy to install, which will be durable and efficient in service and a general improvement in the art.

With the above and other objects and ad-

vantages in view the invention consists in the details of construction to be hereinafter more fully described and claimed and illustrated in the accompanying drawings, in which:

Figure 1 is a fragmentary elevation of an open hearth furnace showing one of my door frames mounted therein,

Figure 2 is a longitudinal section through the furnace looking at the door frame from the inside thereof,

Figure 3 is a cross section on the line 3—3 of Figure 1,

Figure 4 is a perspective view of one form of frame,

Figure 5 is a front elevation of another form of frame,

Figure 6 is a rear view thereof,

Figure 7 is a front elevation of another modification and

Figure 8 is a rear view thereof.

Referring more particularly to the drawings and especially to Figure 4, I have shown the door frame as constituting an arch-like body 10 which is hollow and which includes a lower or main portion defined by legs 11 located at opposite sides of an arched opening 12. The top of the body portion is formed at its forward corners with upstanding hollow pillars or pedestals 13, which, however do not extend entirely to the rear face so as to leave a horizontal ledge 14. Connected with the bottom portion of the legs 11 are inlet pipes 15 for water and connected with the tops of the pedestals 13 are outlet pipes 16. These pipes are provided for the purpose of permitting a constant flow of water to be maintained throughout the hollow frame so as to effect cooling and consequently prevent buckling, warping or other distortion thereof.

In Figures 5 and 6 I have shown a slight modification in which the construction is primarily the same as in the above described form except that the height of the ledge 17, which corresponds to the ledge 14 is considerably greater, the pedestals 18 being correspondingly shorter. Furthermore the ledge 17 is recessed out or formed with a depressed portion 19 which is substantially the same height as the ledge 14 and which is of practically a length equal to the distance between the pedestals 18.

In Figures 7 and 8 the structure is generally the same except that the arched opening 20 is not of uniform size throughout

but extends into a larger space between the rear portions of the legs 21. The same ledge 22 is provided to correspond with the ledge 14, but this ledge is cut back as shown at 5 23 to provide an overhang 24 at the top of the arch opening 20.

Another important feature of difference in this third form is the provision of longitudinally extending ribs 25 on the front, 10 which ribs extend from the very bottom to the top of the pedestals 26. Furthermore I provide the confronting faces of the pedestals with guides 27 within which is a slidably mounted door 28 provided at its 15 upper edge with a flange 29 serving as a handle. Across the top of the pedestals I provide a connecting beam 30 provided with holes 31.

In Figures 1 to 3 inclusive I have illustrated my door frame construction as built into an open hearth furnace of a well recognized type. In these figures the letter A designates the walls of the furnace while B represents the top thereof. On the outside of the walls are the usual pillars C against the sides of which are disposed the channel irons D which support the edges of the roof arch E. The upper ends of the pillars are here shown as connected by stay 20 rods F which are located above the arch roof. Ordinarily the door frames or doors are nothing more than brick arches between the pair of pillars and this brick work generally becomes damaged by the loading 25 machine so that in time they are destroyed or at least weakened so that they may fall in and consequently necessitate shutting down of the furnace.

In applying any form of the above described door frames to this furnace, the frame is located between two successive pillars C, the sides of the frame coming to the pillars so that brick work at this point will be unnecessary. In the forms of the 40 device shown in Figures 4 and 5, the space between the pedestals is intended to be bricked up as indicated at G in Figure 1 while the space below the bottom of the frame is bricked up as indicated at H. The 45 brick work G may extend up and in fact really should reach to the iron work holding the roof. In the form shown in Figures 7 and 8 this top brick work may be omitted owing to the provision of the slidably mounted door.

From the foregoing description and a study of the drawings it will be apparent that the door frames constituting my invention are a manifest improvement in 50 every respect, the pedestals at the upper ends of the frames operating to support and brace the channel irons which hold the roof. In the ordinary construction the brick arches break down and the channel 55 irons of the roof construction then warp or

sag which is likely to cause destruction of the roof itself. Furthermore the breaking down of the arches permits too great a quantity of heat to escape so that the furnace loses its efficiency and must be shut 70 down while repairs are made. Another point of advantage is that the frames in this case are hollow and are supplied with water which circulates therethrough and which has a cooling action which will prevent warping and buckling of the iron. 75

It is to be observed that the present structure is most advantageous when compared with others and is far superior to the various furnaces of the well known types of 80 construction. First, the channel holding the roof on the old type of furnace bends down under the weight and this same weight then comes upon the frames and bends them out of shape so that they can never again be 85 fitted into place. This naturally will leave a hole which permits a draft and causes the escape and loss of gas. In the present device the weight does not bear down on the frame and as a result the frame does not 90 become distorted but always fits properly within its place. It is often the case that the top of the furnace is raised for some reason or other which may occur in the operation or in the course of time. In such 95 instance, an old frame cannot be used unless remodeled. This disadvantage does not occur in my construction for when the top is raised it is merely necessary to fill in the resultant opening with additional bricks. 100

While I have shown and described the preferred embodiment of my invention it is of course to be understood that I reserve the right to make such changes in the form, construction and arrangement of parts as 105 will not depart from the spirit of the invention or the scope of the subjoined claim.

Having thus described my invention I claim:

In a furnace structure, a plurality of upright beams, horizontally disposed beams located inwardly of the upright beams, tie rods connecting the upper ends of the upright beams, metallic door members located between the upright beams, brick work surrounding the door members and filling the spaces between the upright beams and extending upwardly to the horizontal beams, and an arch of brick formation extending between the horizontal beams, each door member being formed with an arch shaped opening and provided at its top with 110 standing spaced pedestals of less thickness than the body of the door member to define a horizontal ledge and to further define an 115 opening between the pedestals, and a movably mounted door for closing the opening. 120

In testimony whereof I affix my signature.

ANDREW GANTZ.
